371.

John Elgar.

The Schedule referred to in these Letters Patent, and making part of the same, containing a description in the words of the said John Elgar, himself, of his improvement in the mode of constructing the revolving platform employed upon Rail Roads.

Scall whom it may concern.

Doth know that I John Elgar, civil engineer of the City of Philadelphia, in the State of Pennsylvania, have invented, certain improvements in the mode of constructing the revolving platform, employed upon Rail Roads, for the purpose of turning rail-way carriages, and that the following is a full, and exact description thereof. — I usually make the revolving platform, and the car, with-in which the projecting spindle which sustains it turns, of cast iron, as being the most durable material. The upper side of the Platform, I, in general make concave over a considerable part of its diameter, say to the distance of thirty inches, from the centre, giving to it a rise of two or three inches, from this rise to the periphery which constitutes the part upon which the wheels are to roll, and next, it is made flat or has but a slight inclination towards the outer edge. When the car passes upon this, the advance wheels rise over a portion of the concave part, and having passed this, the tendency of the car is to remain in its place, whilst the platform is turned. — Although I think the concave form of the upper side of the platform the best, it is by no means an essential point, and it may be made flat if preferred. — There are no rails, or grooves, upon the surface, of the Platform, as it is not intended that the wheels, shall be sustained by their tread, but by the edge of their flanges, whilst upon it. — The Platform is consequently placed sufficiently low, that to raise the wheels, and to bring in the right position for that purpose, whether intended to pass over, or to turn around. — The under side of the platform I generally make concave, so that the water which may run from its top, will not have any tendency to fall along it, towards the spindle upon which it turns; or this may be prevented by the well known mode of forming a

ring, or field on the under side of a platform which descends below the general surface, which at the same time tends to lengthen the platform. — From the center of the platform, a spindle extends into a socket prepared to receive it. Lowly make this spindle about 30 inches long, about 1 1/2 inches diameter at top, where it projects from the platform and tapering down to about three inches at the bottom, where it rests in the socket, exposing hemispherical end. — This invention, however, may be used, according to its construction. — The socket is which the spindle turns, and which is its only support, has a collar surrounding the cavity at its upper end, which embraces the spindle; the socket rises into the concavity of the platform, when it is made concave, and approaches nearly, but does not touch its under surface. — A projecting flange, surrounds the upper end, which aids in sustaining it firmly in the framework or roadway, in which it is fixed. — When in its place, neither water, or dirt can find its way into the socket, to mix with the oil, or obstruct the action of the machine. — That I claim as my invention, and for which I ask a Patent, is the construction of a rolling platform, for railroads, upon the principle herein before described. — That is, to obtain the rolling motion, by means of a spindle, and socket, without friction, wheels, or rollers, beneath it; and the suspending with rails, and ground, to guide the car, — whether the same be constructed, in the exact way specified, or in any other producing a like effect, and acting on the same principle.
